CLAIM

I claim the ornamental design for a display screen with a graphical user interface, as shown and described.

DESCRIPTION

The sole FIGURE is a front view of a display screen with a graphical user interface, showing my design.

The outermost broken lines show a display screen and form no part of the claimed design. All other broken lines are for the purposes of illustrating portions of the display screen with a graphical user interface and form no part of the claimed design.

1 Claim, 1 Drawing Sheet
